UNITED STATES PATENT OFFICE.

DENNIS E. LAHEY, OF LOUISVILLE, KENTUCKY.

RAILWAY SWITCH.

1,421,963.

Specification of Letters Patent. Patented July 4, 1922.

Application filed February 18, 1922. Serial No. 537,489.

To all whom it may concern:

Be it known that I, DENNIS E. LAHEY, a citizen of the United States, residing at Louisville, in the county of Jefferson and State of Kentucky, have invented certain new and useful Improvements in Railway Switches, of which the following is a specification, reference being had therein to the accompanying drawing.

10 This invention relates to improvements in railway trackage and more particularly to improvements in switches.

The primary object of the invention is to insure the safety of trains passing over the main track or through a switch and to prevent damage of the track at the switch points.

Another object of the invention is to furnish improved means for protecting the switch points so that the switch points in use will be protected from wear and from danger of being split by a sharp flange on the wheel of a passing train, and when a switch point is not in use it will be shielded 25 from loose or broken parts hanging from passing trains.

A still further object of the invention is to furnish means for preventing spreading of the stock rails at the point where the 30 switch is located.

A still further object is to provide improved guard rails and to tie the same to the stock rails in such manner that the guard rails cannot shift away from the stock 35 rails or toward the stock rails. Consequently the throats between the guard rails and the stock rails will remain at substantially constant width and the distance between the stock rails will be the same at all 40 times.

Another feature of the invention resides in an improved guard rail constructed from a piece of specially made rail and so shaped as to facilitate the housing of the switch 45 points beneath plates supported by the guard rails.

A further object is to provide means combined with the guard rails for elevating of parts hanging from the train to pass over the guard rails and switch points so that a loose brake beam or chain for instance suspended from the train will not catch in any portion of the track at the point where the switch is located and tear any portion of 50 said track away.

Another object is to provide non-spread-

ing means for the stock rails having seats to accommodate the stock rails and guard rails, the seats being so arranged that the guard rails will project above the stock rails. 60

With the foregoing objects outlined, and with other objects in view which will appear as the description proceeds, the invention consists in the novel features herein-after described in detail, illustrated in the 65 accompanying drawings and more particularly pointed out in the appended claims.

Referring to the drawings:

Figure 1 is a top plan view of a portion of a railway track at the point where the 70 switch is arranged and showing the preferred embodiment of the invention.

Fig. 2 is a transverse vertical sectional view taken on line 2—2 of Fig. 1.

Fig. 3 is a similar view taken on line 3—3 75 of Fig. 1.

Fig. 4 is a longitudinal sectional view of the ties and tie bars and a side view of one of the improved guard rails.

Fig. 5 is a perspective view of one of the 80 guard rails.

Fig. 6 is a side view of the base for the improved guard rails.

Fig. 7 is a detail sectional view taken on line 7—7 of Figure 1. 85

Fig. 8 is a perspective view of one of the cover plates which is adapted to be secured to one of the guard rails and to cooperate with said guard rail to house one of the switch points. 90

Fig. 9 is a top plan view of a track at the point where the switch is arranged and showing a modification of the invention.

Fig. 10 is a vertical longitudinal sectional view of the construction shown in 95 Fig. 9.

Fig. 11 is a detail transverse sectional view of a portion of the construction shown in Fig. 9.

Fig. 12 is a similar view taken on a line 100 extending through one of the switch points.

In the drawings 1 and 2 designates stock rails and 3 and 4 indicate switch rails or points. The switch points are rigidly connected together by tie rods 5 and 6 and the latter rod is provided with an operating member 7 which may be actuated by any suitable mechanism (not shown).

Arranged between the the stock rails at the place where the points of the rails 3 and 110 4 cooperate with the stock rails, are a plurality of guard rails 8 and 9, each of which

is formed in a particular manner to accomplish the objects set forth in the foregoing description.

Referring to Figs. 5 and 6, it will be seen that each guard rail is formed from a piece of specially designed rail and it includes a base 10, web 11 and head 12. The web is cut away as shown at 13 to permit the head to be bent downwardly towards the base as shown at 14 in Figures 4 and 5. At the point 15 an arc-shaped portion is removed from the web of the rail and then the base is bent up into this recess as shown at 16 in Figures 4 and 5. The opposite end of the guard rail is cut away as shown at 17 to permit the end of the head 12 to be bent downwardly towards the base as shown at 18 in Figures 4 and 5.

In addition to being shaped in the manner just set forth, the guard rail is bent into substantially Z-shape as shown at 19 and the end 20 is curved away from the stock rail with which the guard rail is associated as shown at 21 in Figure 1.

A pair of guard rails is employed and each guard rail is made in the same manner with the exception that one is formed to cooperate with the stock rail 1 while the other is shaped to cooperate with the rail 2. After the guard rails are made up in the foregoing manner, they are secured to the ties by any suitable fastening means such as the spikes 22 and chairs or support plates 23 are arranged between the guard rails and certain of the ties.

The guard plates also rest on tie bars 24, best shown in Figs. 2 and 3, and these tie bars are secured to certain of the ties by suitable fastening means such as bolts or spikes 25. It will be noted that the extreme ends 26 of these tie bars are bent upwardly in the form of hooks which form recesses into which the outer flanges of the stock rails fit, and these hooks prevent any outward or upward movement of the stock rails so that spreading of the track is prevented. It will be noted that the stock rails rest on the tie bars 24 and that these bars function as seats or chairs for the stock rails. The tie bars also have raised surfaces 27 functioning as seats for the guard rails. These seats or surfaces 27 are arranged above the surfaces which contact with the bases of the stock rails, so that the guard rails are positioned above or at a greater height than the stock rails and they thus function to keep the wheel flanges to the track. The tie bars are also provided with hooks 28 which engage the flanges of the guard rails and prevent said guard rails from moving inwardly or away from the stock rails. By this construction it will be understood that the stock rails are prevented from spreading and that the guard rails are always held a fixed distance inwardly away from the

stock rails, and in order to prevent the guard rails from moving toward the stock rails filler blocks 29 are arranged in the spaces between the stock and guard rails and are secured to the rails by bolts 30.

In addition to the hooks 26 and 28 the stock rails and guard rails are also tied together by clamps 31, best shown in Fig. 7, having hooked ends 32 which engage the flanges of the rails and insure the positioning of the same at a fixed distance apart.

The outer edges 33 of the cover plates 34 are beveled downwardly and outwardly in order to accommodate flanges of different thicknesses and to cooperate with the flanges of modern wheels. This feature is considered important as a straight surface on the outer side of the guard rail will not accommodate the flanges of wheels made at the present time.

Each guard rail is provided with a cover plate 34 secured to the head of the rail by any suitable means such as screws 35. From the point where the bend 19 is provided in the guard rail to a point adjacent to the end 18 of the guard rail, the plate 34 forms a shed as shown at 36 in Fig. 3 and this shed permits the points of the rails 3 and 4 to be housed when the same are not cooperating with either one of the stock rails. By this construction the point is protected when the same is not in use and that the head of the same will be prevented from wearing. The plates 34 may be made of either rolled carbon steel or of manganese steel but I prefer to employ the latter material in manufacturing the plates. At the entrance to the switch, ramps or guides 37 are provided and these ramps, as best shown in Fig. 4, have inclined upper surfaces 38 which gradually incline from the end 39 upwardly toward the end 40. By this construction any loose part, such as a chain hanging from the train, will be guided upwardly so that it will pass through the throat between the guard rail and stock rail without liability of catching on any portion of the track and injuring the same. On the web 11 of the guard rail an aperture 45 is formed to allow the passage of the electrical signal wires which are attached to the switch points 3 and 4.

It will be noted that the upward bend of the base of the guard rail as shown in 16 provides a recess 43 to accommodate passage 120 of the rod 6.

From the foregoing description, I believe that the construction and operation of the preferred embodiment of the invention may be readily understood and I will now describe the modification shown in Figures 9 to 12 inclusive. In this construction the guards are preferably formed of channel-shaped castings 50 as best shown in Figure 11 and they are provided on their upper 130

surfaces with wear resisting plates 51. The ends of the guard castings are secured in any desired manner to V-shaped castings 52 having inclined upper surfaces 53, as shown in Figure 10. These inclined upper surfaces function to guide any loose parts suspended from the train, over the point where the switch is located, and cover plates 54 extend between the castings 50 so that the portion 5 of the ties at the points where the switch is arranged is entirely covered. In this construction the switch points are also housed when the same are not in use and to permit this a space is left between one end of a 10 guard casting 50 and one of the end castings 52, and the points are adapted to move into these spaces as shown at 55 in Fig. 9. By referring to Fig. 12 it will be seen that the switch point 56 may move beneath the 15 wear plate 51 and into the space 57 so that the switch point will be housed when not in operation.

The castings 50, plates 51 and end castings 52 are all rigidly connected together so that 20 they in effect form a unit and this unit is connected to the stock rails by means of bolts 58, as shown in Fig. 11, which pass through filler blocks 59 arranged between castings 50 and the stock rails. In this a tie bar 60 extends beneath the track and has hooks 61 at its end for tying the stock rails together and preventing the same from spreading.

In view of the foregoing, I believe that 25 persons skilled in the art will have no difficulty in understanding the invention or manufacturing the construction disclosed, and I am aware that changes may be made in the details set forth without departing from the spirit of the invention as expressed 30 in the following claims.

What is claimed and desired to be secured by Letters-Patent is:

1. In a railway track, the combination 45 with stock rails and movable switch points cooperating therewith, of guard rails arranged between the stock rails, each guard rail being bent intermediate its ends to provide a recess, and plates carried by the guard rails and arranged over the recesses for 50 housing the switch points.

2. In a railway track, the combination 55 with stock rails and movable switch points cooperating therewith, of guard rails arranged between the stock rails and having the ends of their upper surfaces inclined downwardly, and means carried by said guard rails for housing the switch points when the same are not cooperating with the stock rails.

60 3. In a railway track, the combination with stock rails and movable switch points 65 cooperating therewith, of guard rails arranged between the stock rails and carrying means for housing the switch points when the same are not cooperating with the stock

70 rails, each of the guard rails being of substantially Z-shape in plan and provided at one end with a curved extension directed away from the stock rail with which the guard rail cooperates.

4. A combination as claimed in claim 3 in which the upper surfaces of the ends of said guard rails are inclined downwardly.

5. A combination as claimed in claim 3 in which the means for housing one of the 75 switch points includes a plate supported by the last mentioned guard rail.

6. A guard rail formed of a piece of standard rail having the web cut away at the ends and the head inclined downwardly 80 at the ends toward the base, said rail being provided intermediate its ends with a portion arranged substantially at right angles to the end portions, and one end portion being provided with an extension which is 85 curved.

7. A guard rail as claimed in claim 6 in which one end portion of the rail has its web cut away and the base bent upwardly 90 into the recess formed by said cut.

8. In a railway track, the combination with stock rails and movable switch points cooperating therewith, of guard rails arranged between the stock rails and carrying means for housing the switch points when 95 the same are not cooperating with the stock rails, filler blocks arranged between the guard rails to maintain the guard rails at a fixed distance from the stock rails, and tie bars securing the guard rails, filler blocks 100 and stock rails together.

9. In a railway track, the combination with stock rails and movable switch points 105 cooperating therewith, of guard rails arranged between the stock rails and having the outer surfaces of their heads inclined downwardly and outwardly, and means carried by the guard rails for housing the switch points when the same are not cooperating with the stock rails.

10. In a railway track, the combination with stock rails and movable switch points 110 cooperating therewith, of guard rails arranged between the stock rails and carrying means for housing the switch points when the same are not cooperating with the stock rails, and ramps having inclined upper surfaces arranged between the guard rails for guiding any loose parts hanging from the train through the throats arranged between 115 the guard rails and the stock rails.

11. In a railway track, the combination with stock rails and movable switch points 120 cooperating therewith, of guard rails arranged between the stock rails and carrying means for housing the switch points when the same are not cooperating with the stock rails, and tie bars arranged beneath the stock rails and provided with hook ends engaging the flanges of the stock rails.

12. A combination as claimed in claim 11 in which the tie bars are provided with raised surfaces which engage the bases of the guard rails for holding the upper surface of the heads of the guard rails above the upper surfaces of the heads of the stock rails.

13. In a railway track, the combination with stock rails and movable switch points 10 cooperating therewith, of guard rails arranged between the stock rails and carrying means for housing the switch points when the same are not cooperating with the stock rails, and tie bars connecting said stock 15 rails and provided with hooks which engage said guard rails for preventing the same from moving toward one another.

14. In a railway track, the combination with stock rails and movable switch points 20 cooperating therewith, of guard rails arranged between the stock rails, a tie bar extending entirely across the track and having

hooks at its outer ends engaging the outer portions of the flanges of the stock rails, hooks arranged intermediate the ends of 25 said tie bar and engaging the inner portions of the flanges of the guard rails for preventing said guard rails from moving towards one another, filler blocks arranged between the guard rails and stock rails for maintaining 30 said guard rails and stock rails a fixed distance apart, and other tie bars having hooked ends engaging the flanges of the guard rails and stock rails for aiding in holding said guard rails to said stock rails. 35

15. A combination as claimed in claim 14 in which the guard rails carry housings for the switch points.

In testimony whereof I hereunto affix my signature in the presence of two witnesses. 40
